(57) **CLAIM**

The ornamental design for a sole for a slip-on marching band shoe, as shown and described.

DESCRIPTION

FIG. 1 is a bottom perspective view of a first embodiment embodying our new design of a sole for a slip-on marching band shoe for the right foot of user;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a front elevational view of a second embodiment sole for a slip-on marching band shoe for the left foot of a user;

FIG. 9 is a rear elevational view thereof;

FIG. 10 is a right side elevational view thereof;

FIG. 11 is a left side elevational view thereof;

FIG. 12 is a top plan view thereof; and,

FIG. 13 shows a bottom plan view thereof.

The broken lines depict environmental structure associated with the sole for a slip-on marching band shoe in a condition of use. The broken lines and structure they depict form no part of the claimed design.
